METHOD OF MAKING A FINGER RING

Tony E. Foster, Indianapolis, Ind., assignor to
Herff Jones Co., Indianapolis, Ind., a corpora-
tion

Application September 27, 1934, Serial No. 745,672

7 Claims. (Cl. 29—160.6)

This invention relates to the method of making a finger ring, and particularly that type of ring commonly known as an "all metal" or "stone" ring used extensively with fraternal, school or class emblems imposed thereon, and is a continuation in part of my Patent No. 1,947,254, issued February 13, 1934, for Method of making a finger ring.

The principal object of the invention is to produce a ring of this general character which is formed of two different metals, usually gold and silver, in such manner as to give the desired weight, appearance, thickness and wearing qualities while enabling the cost of the material to be substantially reduced. It has been common practice to form rings with a base of cheaper metal, such as silver, upon which a gold facing, of sufficient thickness to provide wearing qualities, is secured by soldering or fusing. It is the purpose of this invention, however, to utilize this principle in constructing a ring with a silver filling which may have a solid gold finger band.

One feature of the invention resides in the formation of a surrounding wall in the formed blank 25 in which the filler is embedded.

Another feature resides in the covering of the exposed surface of the filler with a gold or precious metal plate providing an overlay so that no part of the filler will be exposed, but will be entirely embedded within the enclosing structure 30 of precious metal.

Another feature of the invention resides in the formation of the several pieces and their assembly while the structure is in a substantially flat or extended form before being bent into circular or ring-like formation.

The full nature of the invention will be understood from the accompanying drawing and the following description and claims:

In the drawing, Fig. 1 is a perspective view of a finger band blank having a recessed central portion formed therein for receiving the filler. Fig. 2 is a perspective view of the filler blank. Fig. 3 is a perspective view of the overlay blank. Fig. 4 is a composite perspective view showing the finger band and filler blanks after being formed and the overlay blank positioned to be laid thereover. Fig. 5 is a perspective view of a central vertical section through the composite blank with the filler and overlay in place before forming the ring. Fig. 6 is a perspective view of a section through the formed ring. Fig. 7 is a perspective view of a section showing a modified form wherein the filler is placed upon an unrecessed finger band blank. Fig. 8 is a similar

view of the form shown in Fig. 7 after being struck. Fig. 9 is a similar view of the structure shown in Fig. 8 showing an overlay blank covering the entire finger band blank.

In the drawing there is illustrated in Fig. 6 a section through a finger ring having a finger band 10, a crown 11 upon which an emblem or the like may be mounted, a filler piece 12 and an overlay 13. The finger band, crown and overlay are of precious metal, such as gold, whereas the filler piece 12 is of a baser metal, such as silver. The invention herein described contemplates a ring of this character formed either with or without the overlay 13. Wherein the overlay is employed, the filler is entirely inclosed so as not to be exposed. Thus, the ring has the appearance and wearing qualities of a solid gold ring. Wherein the overlay 13 is eliminated, a portion of the filler 12 will be exposed but will be on the inner surface of the ring so that it is hidden from view when the ring is worn.

The first step of one of the methods, as illustrated in Fig. 1, contemplates the provision of a substantially flat blank having extended arm portions 10a which eventually form the finger band 10. Intermediate said arm portions there is a central recessed portion 14 where the metal is cut away to receive the filler 12.

In forming the blanks, whereas they are herein illustrated as being flat, it will be appreciated that they may be slightly curved or extend slightly in different planes without departing from the fundamental requirement of the method. Such fundamental requirement is that the blank be sufficiently flat in form to be conveniently stamped or struck either before or after the filler is secured thereto. This procedure permits of an emblem or design 15 to be struck on the sides of the finger band blank while in its substantial flat form.

As illustrated in Fig. 2, there is a filler piece 12 shaped to conform substantially with the recess 14 but smaller in area so as to leave an appreciable margin about the edge of the filler for the purpose hereinafter described.

In Fig. 3 there is illustrated an overlay 13 formed of precious metal which is thinner than the filler 12, and of such area as to overlap the filler 12 and extend to the edges of the finger band blank shown in Fig. 1.

After the formation of the above blanks, the finger band and filler blanks may be stamped either separately or together in a suitable die to provide a formed recess 14a in the finger band blank with shoulders 16 and a curved crown por-

tion 11a, the recess 14a to be surrounded by walls 17. The filler piece 12 is thereby formed to provide a central portion 14b corresponding in contour to the formed portion 14a so as to seat and fit snugly therein surrounded by the struck-up walls 17. Thus, the filler forms an inlay completely surrounded by the precious metal with its upper or exposed surface smooth and flat to receive the flat overlay blank 13. The assembly 10 may be viewed in cross section as illustrated in Fig. 5. The composite blank is then bent into shape to form the ring illustrated in Fig. 6.

The same results are secured by stamping or striking the finger band blank separately from the filler blank in the same die and then fitting and securing them together. However, the more practical method is to lay the filler blank upon the finger band blank and either temporarily or permanently secure them together and then strike 20 or stamp them. Either method will result in the form illustrated in Fig. 5, but the former method eliminates the requirement of a male die member. A flat die block may be used, the filler blank performing the service of a male die member. It is immaterial as to whether or not the filler blank is formed separately from the finger band blank as illustrated in Fig. 2. The same results are accomplished wherein the metal 25 of the filler blank comprises a soldered or otherwise secured inlay in the finger band blank. However, it is preferable to follow the above method wherein the filler blank 12 is of less width than the corresponding portion of the finger band blank. This permits of the surrounding exposed surface of the filler blank being formed up into the walls 17 so as to completely 30 embrace the filler.

In the modified forms illustrated in Figs. 7, 8 and 9, the method may be followed wherein the finger band blank 100 is not recessed as at 14. The filler blank 112 may be laid upon the blank 100 which is of the same thickness throughout. These blanks may be struck separately or, more conveniently, as above described, they may be 45 struck together, the filler blank thereby taking the place of a male die. The result is, as illustrated in Fig. 8, that the unrecessed finger band blank is formed to provide the curved recess 11a with the design or emblem 115 formed thereon 50 to provide the concave cavity for recessing the thickened filler blank 112. Here, again, it is immaterial as to whether or not the filler blank is temporarily or permanently secured to the surface of the finger band blank. Fig. 9 illustrates 55 the same with the gold overlay 113 extending from end to end of the finger band blank. This may be preferable wherein, with this modified method, it may be desirable to reduce the thickness of the finger band blank. Such reduction in 60 thickness may, therefore, be compensated for by extending the overlay blank 113 throughout the full length thereof.

From the foregoing, it will be observed that the blank with the filler is formed to shape with the design or emblem 15 and the thickened recessed crown portion while in substantially flat extended form which permits of the ready formation of the ring thereafter with the flat crown portion for receiving a superimposed emblem or stone. 65 This is accomplished by stamping the blank and filler either separately or while secured together in the same die, the filler being entirely surrounded by the precious metal of the blank. In addition thereto, the filler may be entirely 70 closed by the addition of the overlay blank to pro-

vide precious metal over the interior surface of the ring.

The invention claimed is:

1. The method of making a finger ring consisting in forming a finger band blank of precious metal with an enlarged central portion and finger band portions extending away from each side thereof in substantially the same plane, positioning a substantially flat filler blank of baser metal over the enlarged portion, striking the filler and blank in the same die to form an emblem on one side of the finger band blank and an enlarged recess on the other side thereof in which said filler is imbedded, the other side of said filler being substantially flat, and thereafter 15 bending said finger band blank and filler to provide a ring with the filler on the inside thereof.

2. The method of making a finger ring consisting in forming a flat finger band blank of precious metal with an enlarged central portion and finger band portions extending away from each side thereof in substantially the same plane, positioning a substantially flat filler blank of baser metal but of less width than the central portion of the finger band blank thereover, striking the filler and blank in the same die to form an emblem on one side of the finger band blank, and a concave recess on the other side surrounded by a wall portion formed from the uncovered periphery of the enlarged central portion, said filler 30 being imbedded within said formed recess with its exposed surface substantially flat, and thereafter bending said finger band blank and filler to provide a ring with a filler on the inside thereof.

3. The method of making a finger ring consisting in forming a finger blank of precious metal with an enlarged central portion of substantially uniform thickness and the finger band portions extending away from each side thereof in substantially the same plane, positioning a substantially flat filler blank of baser metal over the enlarged portion, positioning the finger band blank over a female die member, striking the filler and finger band blank with a substantially flat die member to form an emblem and concave surface 45 on the exposed side of the finger band blank through the medium of the filler, said filler thereby being increased in thickness and imbedded in the formed finger band blank with the exposed surface of the filler substantially flat, and thereafter 50 bending said finger band blank and filler to provide a ring with a filler on the inside thereof.

4. The method of making a finger ring consisting in forming a finger band blank of precious metal with an enlarged central portion of substantially uniform thickness and finger band portions extending away from each side thereof in substantially the same plane, positioning a substantially flat filler blank of baser metal but of less width than the central portion of the finger band blank thereover, striking the filler and blank in the same die to form an emblem on one side of the finger band blank, and a recess on the other side surrounded by a wall portion formed from the uncovered periphery of the enlarged central portion, said filler being imbedded within said formed recess with its exposed surface substantially flat, securing an overlay blank of precious metal over the substantially flat surface of the filler, and thereafter bending said 60 finger band blank and filler to provide a ring with a filler on the inside thereof.

5. The method of making a finger ring consisting in forming a finger blank of precious metal with an enlarged central portion and the finger 75

- band portions extending away from each side thereof in substantially the same plane, positioning a filler blank of baser metal over the enlarged portion, positioning the finger band blank over a female die member, striking the filler and finger band blank with a substantially flat die member thereby increasing the thickness of the filler and form, an emblem and recess on the exposed side of the finger band blank through the increased thickness of the filler, said filler thereby being imbedded in the formed finger band blank with the exposed surface of the filler substantially flat, securing an overlay blank of precious metal over the substantially flat surface of the filler, and thereafter bending said finger band blank and filler to provide a ring with a filler on the inside thereof.
6. The method of making a finger ring consisting in forming a finger band blank of precious metal with an enlarged central portion and the finger band portions extending away from each side thereof in substantially the same plane, positioning a filler blank of baser metal over the enlarged portion, mounting an overlay blank of precious metal over the filler blank, positioning the finger band blank over a female die member, striking said blank with a substantially flat die

member to form an emblem and recess on the exposed side of the finger band blank through the medium of the filler, said filler thereby being increased in thickness and imbedded in the formed finger band blank with the exposed surface of the overlay blank substantially flat, and thereafter bending said formed struck blanks to provide a ring with a filler encased by the precious metal.

7. The method of making a finger ring consisting in forming a finger band blank of precious metal, positioning a substantially flat filler blank of baser metal thereon, and simultaneously striking said combined blanks with the finger band blank on the female side of the die and the filler blank on the male or hammered side of the die, the force of the stamping operation causing the finger band blank to receive the shape of the female die without substantial variation in the thickness of the metal, while the metal of the filler blank flows to conform with such variation in thickness as is required by the form produced upon the finger band blank and thereafter bending said formed blanks to provide a ring with a filler on the inside thereof.
